UNITED STATES PATENT OFFICE.

MORRIS B. OKUN, OF CHICAGO, ILLINOIS, ASSIGNOR TO THE SENG COMPANY, OF CHICAGO, ILLINOIS.

BED-RAIL FASTENER.

1,346,908.

Specification of Letters Patent. Patented July 20, 1920.

Application filed March 3, 1916. Serial No. 81,861.

To all whom it may concern:

Be it known that I, MORRIS B. OKUN, a citizen of the United States, residing at Chicago, in the county of Cook and State of Illinois, have invented a certain new and useful Improvement in Bed-Rail Fasteners, of which the following is a full, clear, concise, and exact description, reference being had to the accompanying drawings, forming a part of this specification.

My invention relates to bed rail fasteners and has for its object the provision of a new and improved device of this character in which I can construct the entire housing of a single blank of metal. The structure of my invention further permits the rails, both the side and end rails, to remain unbroken throughout their length without being peculiarly notched as heretofore necessary. I have provided improved clamping facilities which will accommodate the rails having squared ends and securely hold them in position.

My invention further contemplates the provision of a structure which is capable of use both for wooden and metal posts, and capable of use both for round and square posts.

I will explain one form which my invention may take more in detail by referring to the accompanying drawing, in which—

Figure 1 is a perspective view of my device shown mounted in place upon a post;

Fig. 2 is a sectional view along line *a* of Fig. 1;

Fig. 3 is a sectional view along line *b*—*b* of Fig. 2;

Fig. 4 is a fragmentary view showing the application of my device to a round post;

Fig. 5 is a fragmentary view showing the device of Fig. 4 as attached to a square post;

Fig. 6 is a fragmentary sectional view showing a modified form of the device;

Fig. 7 is a fragmentary sectional view showing a modified form of the device, and

Fig. 8 is a partial sectional view on line *c*—*c* of Fig. 3.

My improved fastener consists of a housing having two side faces 1 and 2, a top face 3, a back 4, and a strip 5 running parallel to the side 1. The strip 5 has an extension 6 from which a rectangularly extending bracket having the sides 7 and 8 extends. All of the parts thus mentioned

are made of one blank of metal bent into the form shown. The bracket consisting of the arms 7 and 8 supports the end rail 9 shown in dotted lines in Fig. 2, the same being preferably riveted as shown by the dotted rivets 10. The device is fastened, for instance, to a square post as shown more clearly in Figs. 2 and 3 by having the spring plate 11 interiorly of the device, the reinforcing plate 12 interiorly of the bed post 13, and having bolts 14, 14 which clamp all the parts securely together.

Within the housing as thus constructed of one single blank of metal, I provide a block 15 or filler preferably rectangular but hollowed out at 16, 16 as shown to make it lighter and also to permit it to accommodate the bolt 14. This block 15 is held in position by the screw 17 which operates in an elongated slot 18 in the housing. The block 15 has the central wall 19 as shown so that it may serve as the proper abutment for a locking bolt 20 having the finger piece 21. This locking bolt extends through a bridge 22 which is riveted to the side walls 1 and 2 as more clearly apparent from Fig. 2. The various parts which are here shown as being fastened together on this housing may of course be spot welded, thus omitting the use of rivets should this be found desirable.

It will be seen that between the interior surface of the housing and the block 15 there is left an unconfined space running throughout the length of the housing to accommodate the side rail 23. This side rail can thus have squared ends and need not have its ends specially cut as it can enter the full length of the housing as shown most clearly in Figs. 2 and 3. Should it be desired to reverse the side rail 23, then of course the movable block 15 permits the side rail 23 to lie along the same side face and the bottom face of this block.

In Fig. 4 I show a modified form in which the housing is rounded as shown at 24 to accommodate a rounded post 13^a.

In Fig. 5 I have shown this rounded housing as provided with a distance piece or block 25 so that this rounded housing may also be used in connection with a square post.

In Fig. 6 I show a modified form of device in which the side face 2 of the housing has an extending finger 26 which is bent at

right angles thereto and riveted to the side face 1. A loose block 27 may then rest thereon to accommodate the bolt 20.

In Fig. 7 I have shown two arms 28 and 29 bent respectively from the side faces 2 and 1 through which the bolt 20 may pass without the need of the additional reinforcing block 27.

From what has been described it is thought the nature of my invention will be readily clear to those skilled in the art. Having however thus described one form which my invention may take, what I claim as new and desire to secure by Letters Patent is:

1. A bed rail fastener of the character described comprising a housing made of a single blank of metal having a top wall, two side walls and an end wall, said end wall being adapted to abut a corner post, said end wall having an extension thereof forwardly along one side wall, said extension having a longitudinally extending bracket adapted to receive an end rail.
2. A bed rail fastener of the character described comprising a housing made of a single blank of metal having a top wall, two side walls and an end wall, said end wall being adapted to abut a corner post, said end wall having an extension thereof forwardly along one side wall, said extension having a longitudinally extending bracket adapted to receive an end rail, a bridge extending between said side walls, and a side rail clamping bolt mounted in said bridge.
3. A bed rail fastener of the character described comprising a housing made of a single blank of metal having a top wall, two side walls and an end wall, said end wall being adapted to abut a corner post, said end wall having an extension thereof forwardly along one side wall, said extension having a longitudinally extending bracket adapted to receive an end rail, a bridge extending between said side walls, and means cooperating with said bridge to hold a side rail in position.

4. A bed rail fastener of the character described comprising a housing having three rectangularly disposed faces, and means for reversibly securing a demountable angular side rail interiorly of said housing, said means including a bolt and a transversely movable filler loosely supported in the space included by the angle of the side rail in the housing to be permanently carried thereby, said bolt being adapted to lock said filler and side rail in position within said housing.

5. A bed rail fastener of the character described comprising a housing made of a single blank of metal and having three rectangularly disposed faces, and means for reversibly securing a demountable angular side rail interiorly of said housing, said means including a bolt and a filler adapted

to fit into the angular space embraced by the side rail and loosely supported and transversely movable in the housing to be permanently carried thereby, said bolt being adapted to lock said filler and side rail in position within said housing.

6. A bed rail fastener of the character described comprising a housing made of a single blank of metal and having three rectangularly disposed faces, and means for reversibly securing a demountable right angled side rail interiorly of said housing, said means including a bolt mounted on said housing and a filler loosely fitting the rectangular space defined by the side rail and supported in and movable across the housing to be permanently carried thereby, said bolt being adapted to lock said filler and side rail in position within said housing.

7. A bed rail fastener of the character described comprising a housing having three rectangularly disposed faces, and means for reversibly securing the unbroken ends of a demountable side rail interiorly of said housing, said means including a bolt and a filler loosely supported in the housing for transverse movement to be permanently carried thereby, said bolt being adapted to lock said filler and side rail in position within said housing.

8. A bed rail fastener of the character described comprising a housing having three rectangularly disposed faces, and means for reversibly securing a demountable side rail interiorly of said housing, said means including a bolt and a rectangular filler loosely supported in the housing to be permanently carried thereby, said bolt being adapted to lock said filler and side rail in position within said housing.

9. A bed rail fastener of the character described comprising a housing having three rectangularly disposed faces, and means for reversibly securing a demountable side rail interiorly of said housing, said means including a bolt and a hollow rectangular filler loosely supported in the housing to be permanently carried thereby, said bolt being adapted to lock said filler and side rail in position within said housing.

10. A bed rail fastener of the character described comprising a housing having three rectangularly disposed faces, and means for reversibly securing a demountable side rail interiorly of said housing, said means including a bolt and a bodily shiftable filler, means for slidably connecting the filler to the housing, said bolt being adapted to lock said filler and side rail in position within said housing.

11. A bed rail fastener of the character described comprising a housing having three rectangularly disposed faces, and means for reversibly securing a demountable side rail interiorly of said housing, said means in-

cluding a bolt and a filler, a pin connected to the filler and slideable in a slot in the housing, said bolt being adapted to lock said filler and side rail in position within said housing, said side rail when in position being between said filler and said housing.

12. A bed rail fastener of the character described comprising a housing having three rectangularly disposed faces, and means for reversibly securing a demountable side rail interiorly of said housing, said means including a bolt and a filler, means for slidably mounting the filler in the housing, said bolt being mounted in position transversely of said side rail and being adapted to lock said filler and side rail in position within said housing.

13. A bed rail fastener of the character

described comprising a housing having three rectangularly disposed faces, and means for reversibly securing a demountable side rail interiorly of said housing, said means including a bolt and a filler loosely supported in the housing, said bolt being mounted in position transversely of said side rail and being adapted to lock said filler against the side of the rail to hold the side rail in position within said housing.

In witness whereof, I hereunto subscribe my name this 26th day of February, A. D. 30 1916.

MORRIS B. OKUN.
